UNITED STATES PATENT OFFICE.

JOHN B. SWAN, OF DENVER, COLORADO, ASSIGNOR OF ONE-HALF TO LOUIS CSEMICZSKY, OF DENVER, COLORADO.

COMBINED SHADE ROLLER AND CURTAIN BRACKET.

Application filed November 29, 1921. Serial No. 518,508.

To all whom it may concern:

Be it known that I, JOHN B. SWAN, a citizen of the United States of America, residing at Denver, in the county of Denver, 5 in the State of Colorado, have invented certain new and useful Improvements in Combined Shade Roller and Curtain Brackets, of which the following is a specification.

The present invention is directed to improvements in combined shade roller and curtain brackets.

The primary object of the invention is to provide a device of this character so constructed that it can be easily and quickly 15 secured to a window frame, and may be adjusted to support shade rollers of different length, curtains of different widths, and draperies.

A further object of the invention is to provide a device of this nature having brackets 20 formed from single piece blanks of sheet metal so fashioned that they can be easily shaped to the necessary form for ready attachment to the window frame, and when in place thereon will effectively support the shade rollers, curtains, and draperies.

With these and other objects in view, this 25 invention resides in the novel features of construction, formation, combination and arrangement of parts to be hereinafter more fully described, claimed and illustrated in the accompanying drawing, in which:—

Figure 1 is a perspective view of the right hand side bracket.

Figure 2 is a transverse sectional view 30 through the same.

Figure 3 is a sectional view on line 3—3 of Fig. 1.

Figure 4 is a plan view of the blank.

40 The device comprises, as usual a pair of brackets, one only of which is shown, each consisting of a tubular body formed from a single blank of suitable sheet metal. This blank has formed on one end, and centrally 45 thereof, an arm 3, and upon each corner ears 4, said ears being for a portion of their lengths separated from the adjacent ends of the body of the blank by kerfs 5. Each ear has formed therein a perforation 6, and the 50 body a slot 7, the purpose of which will appear later.

In forming the body 2, the blank is rolled on a mandrel, or in any other suitable manner until the side edges are in contacting 55 relation, after which the arm 3 is bent at

right angles to the body, and has formed therein a perforation 8. The ears are then bent, which may be readily accomplished due to the kerfs 5 until they are in the same plane with each other, thus permitting the 60 same to be placed evenly against the upper portion of a window frame. Suitable securing devices 9 are then placed in the perforations 6, and the ears firmly secured to the frame.

The arm 3 is bent outwardly at right angles to the body 2, and thus it will be seen that the body, arms 3 and ears 4 form a unitary structure, and that the arm and ears may be bent to the desired positions should they 70 from any cause become slightly displaced, or should it be necessary to adjust said ears for attachment to a window frame having an uneven surface.

To support a conventional shade roller a 75 tubular bearing 10 is provided, the same being formed from suitable sheet metal, and is adapted to slidably engage in the tubular bodies 2. The bearing 10 has its ends rolled, and is provided at one end with a slot 11 for receiving the usual squared spring 80 pintle of the conventional shade roller.

The bearing 10 carries a clamping screw 12 adapted for travel in the slot 7. Said screw having a winged nut 13 thereon which 85 serves to grip the body 2 adjacent the slot, thereby holding the bearing in proper adjusted position in an obvious manner.

Curtain poles are used, and are of the telescoping type, one section 14 being shown 90 only, the outer end of which is supported in the perforation 8 of the arm 3.

A drapery hanger 15 is employed, and 95 comprises a rod 16, the outer end of which terminates in a right angle arm 17 which lies parallel with the arm 3, the rod 16 being similarly disposed with respect to the pole 14. The inner end of the arm 17 terminates in an upwardly opening hook in which is engaged the arm 3, said arm having its outer end bearing upon the adjacent end of the curtain pole section 14. Thus it will be seen that the drapery hanger can be readily removed or replaced, and when in place will firmly remain in place.

From the foregoing description, taken in connection with the accompanying drawing it is thought the operation and many advantages of the invention will be apparent to those skilled in the art.

It will be understood that while I have shown and described a preferred form of my invention, changes involving omission, substitution, alteration, and reversal of elements, may be made without departing from the scope of the invention.

What is claimed is:—

As a new article of manufacture, a combined shade roller and curtain pole supporting bracket formed from a single blank of rectangular sheet metal, ears formed on the corners of the blank, an arm formed upon one end of the blank and between the adjacent ears, said blank being rolled until the

side edges contact to provide a tubular body, 18 said arm being bent at right angles to the body for supporting a curtain pole, said ears being bent to attach to a window frame, and a tubular bearing slidably mounted in the body, and means for securing the bearing in adjusted positions.

In testimony whereof I have hereunto set my hand in presence of two subscribing witnessses.

JOHN B. SWAN.
